(57) **CLAIM**

The ornamental design for a back cover for a mobile phone case, as shown and described.

DESCRIPTION

FIG. 1 is a perspective view of a back cover for a mobile phone case showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a cross-sectional view thereof taken along line 9-9 in FIG. 3;

FIG. 10 is another cross-sectional view thereof taken along line 10-10 in FIG. 3; and,

FIG. 11 is a perspective view showing the back cover for a mobile phone case in a state of use.

The dash-dash broken lines depicting edges of the article in FIGS. 1 to 10 represent unclaimed portions of the back cover for a mobile phone case which form no part of the claimed design.

The dash-dash broken lines in FIG. 11 depicting an outer bumper portion of a mobile phone case represent environmental subject matter which forms no part of the claimed design.

The dash-dot broken lines are for defining the bounds of the claimed design only and form no part of the claimed design.

1 Claim, 11 Drawing Sheets
